WITNESS:

H. Fleisher
INVENTOR
BY *Victor J. Evans*
ATTORNEY

UNITED STATES PATENT OFFICE.

HENRY FLEISHER, OF GAMBRILLS, MARYLAND.

POISON INDICATOR.

Application filed June 16, 1922. Serial No. 568,749.

To all whom it may concern:

Be it known that I, HENRY FLEISHER, a citizen of the United States, residing at Gambrills, in the county of Anne Arundel and State of Maryland, have invented new and useful Improvements in Poison Indicators, of which the following is a specification.

The object of this invention is to provide a device which is adapted to be attached to a bottle containing poison or other injurious substance for indicating the nature of the contents of the bottle, thus preventing a person from taking some of the contents through mistake.

Another object of the invention is to provide the device with a point so that it can be driven into the cork of the bottle and also with a cork screw.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a view of a bottle showing my device in use.

Figure 2 is a rear view of the device with the cork screw in operative position.

As shown in these views the device is formed of a plate 1 which is made in the form of the well known skull and cross bones. A pair of ears 2 is formed at the bottom of the plate between which is pivotally secured a pointed member 3 which is

adapted to be driven into a cork 4 of a bottle 5 to support the device in upright position on the bottle. A cork screw 6 is pivoted between a pair of ears 7 on the top of the plate. Thus either the cork screw or the pointed member can be swung over upon the back of the plate when not in use. The face of the plate can be painted or otherwise marked to represent a skull, as shown in Figure 1.

It will thus be seen that the dangerous nature of the contents of a bottle provided with my device is clearly indicated and the bottle cannot be mistaken for any other either when in a lighted room or in the dark. If an attempt is made to open the bottle during the night the hand striking the device will readily feel the contour of the device and thus a person will know that he has picked up the wrong bottle. When the bottle is empty the device can be placed on a new bottle by simply withdrawing the pointed member from the cork and placing it in the cork of a new bottle.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A device of the class described comprising a plate made in the form of a skull and cross bones, ears at the bottom of the plate, a pointed member pivoted between said ears, ears at the top of the plate and a corkscrew pivoted between said ears.

In testimony whereof I affix my signature.
HENRY FLEISHER.
